UNITED STATES PATENT OFFICE.

GEORGE H. GILMAN, OF BOSTON, MASSACHUSETTS.

DRILLING MACHINE.

Application filed January 31, 1920. Serial No. 355,494.

My invention relates to drilling machines, and particularly, but not exclusively to those for drilling rock, coal and like formations. It comprehends a machine including 5 mechanism for imparting to a drilling tool either or both an angular and a linear motion or force and in which said mechanism is arranged to form a convenient and compact organization; and further comprehends 10 a convenient arrangement for distributing and controlling the fluid supplies.

My invention will be best understood from the following specification and accompanying drawings, which disclose a specific embodiment of my invention submitted 15 for illustrative purposes, the scope of which will be more fully pointed out in the appended claims.

In the drawings: 20 Fig. 1 shows a longitudinal section of a drilling machine embodying my invention.

Fig. 2 is a section on the line 2—2 of Fig. 1; and

Figs. 3, 4 and 5 respectively show sections on the lines 3—3, 4—4 and 5—5 of Fig. 2.

In the embodiment of my invention herein submitted, I provide a cylinder 1 having a front head structure, indicated as a whole by the numeral 2, and a rear head structure, indicated as a whole by the numeral 3. In the front head structure is supported a drilling tool 4 to which a linear force or motion is imparted by a piston 5, and an 35 angular force or motion by a motor which in the submitted embodiment of my invention comprises the gear members 6 and 7. As submitted, the drilling tool 4 is a drill steel adapted to cut by percussive and rotative 40 action the percussive action being imparted thereto by the piston 5 which, for this purpose, is mounted for reciprocation in a piston chamber 8; formed in the cylinder member, and is provided with an extension or 45 hammer bar 8 which extends into a chamber 21 in the front head structure and is adapted to strike the tool.

Herein the motor for imparting a rotative action to the tool is located rearwardly of 50 the rear end of the piston chamber 8' in the rear cylinder head structure, while the reduction gearing hereinafter referred to, which operatively connects the motor with the tool supporting chuck 9, is located forwardly of the front end of the piston chamber 8' in the front head structure.

For admitting and exhausting motive fluid for causing the piston to reciprocate, any suitable means may be employed. That shown herein is not claimed in this application and only will be described with fullness sufficient to set forth how it is applied to the embodiment of my invention now under consideration.

As illustrated the piston is provided with 65 an internal chamber 10, adapted to be supplied with motive fluid through a preferably stationary plug 11 of tubular formation providing a conduit 12 having lateral ports 13 adapted to be partially or fully closed 70 by the reduced bore 14 of the piston chamber which the plug fits. Extending through the wall of the piston and affording communication between the internal chamber and the groove 15 on the exterior surface of 75 the piston is a passage 16 which, when the piston is in the forward end of its stroke and after the ports 13 are throttled or closed, establishes communication between the interior piston chamber and the front 80 end of the cylinder by means of the groove 17 formed in the interior surface of the cylinder.

When the piston is at the rear end of its stroke, motive fluid entering the interior 85 piston chamber 10 by way of the conduit 12 and its ports 13 passes to the rear end of the cylinder through the grooves 18 on the exterior surface of the plug.

When the piston is in the forward end of 90 its stroke, motive fluid from the rear cylinder chamber exhausts through an exhaust port 19, while the hammer bar 8 is so formed that when the piston is at the rearward end of its stroke, said hammer bar withdraws 95 from the bore 20 of the front cylinder head and permits the motive fluid at the front end of the cylinder to pass into the chamber 21 in the front cylinder head whence it may exhaust to the atmosphere or to the bore 44 of 100 the drill steel.

I may in addition to the means just described, also control the admission or exhaust of motive fluid by means of a valve 105 such as is termed in the art a "distributing valve", that is to say, a valve independent of the piston which controls all or part of the events or periods of the fluid cycle. As is obvious, I may cause the operation of the piston by fluid controlled by this valve alone. The valve in the embodiment submitted is in 110 the form of an annular shell valve 23, mount-

ed in the rear head structure and concentrically arranged with the chuck rotating motor so as to be surrounded thereby. The opening 24 of the valve serves to establish communication between the motive fluid supply passage 37 and the bore 12 of the plug 11.

The valve is formed with a constant pressure face 25 and a larger face 26 to and from which motive fluid is admitted and exhausted by means of a kicker passage 27 having ports 28 and 29 controlled by the piston. When the piston moves toward the forward end of its stroke, motive fluid is exhausted from the passage 27 through the port 28, which is then uncovered by the piston, the motive fluid passing to the atmosphere when the piston uncovers the exhaust port 19. When the piston moves toward the rearward end of its stroke motive fluid is admitted from the interior chamber 10 of the piston to the port 29 by way of the piston port 16 and groove 15.

When the piston is at the forward end of its stroke, the valve is at the forward end of its travel and in this position connects the rearward end of the cylinder to the exhaust passage 30 by means of a passage 31 formed in the valve casing and a groove 32 formed on the exterior surface of the valve. Further, when in this position it admits motive fluid by means of a passage 34, then uncovered by the rear end of the valve, to the front piston chamber.

When the piston is at the rearward end of its stroke the valve is at the rearward end of its travel and in this position closes the rearward end 31' of the passage 31. It then admits motive fluid to the rear end of the cylinder by means of a passage 33 formed in the valve casing and then uncovered by the front end of the valve, the passage 33 communicating with the passage 31 as may be understood by an inspection of Fig. 2. Further, when the valve and piston are in their rearward positions motive fluid is exhausted by means of the valve from the front end of the cylinder through the passage 34 which then is put in communication with the exhaust passage 30 by means of the groove 32 on the valve.

In order to increase the capacity of the forward piston chamber and thereby aid in reducing the pressure of the air throttled by closure of the ports 13, if this action is availed of, and in any case, to aid in maintaining the pressure admitted to said chamber, I may provide the holes 35 formed in the cylinder wall and communicating with the groove 17. These holes may if desired communicate with the chamber 36 in the front head structure further to augment the capacity of the front cylinder chamber.

It will be noticed that the hammer bar when reciprocating tends alternately to com-

press and rarefy the fluid in chamber 21. To prevent this action which would tend to slow up the piston if not eliminated, I may provide a passage 22 establishing communication between the chamber 21 and the atmosphere. This passage which I term a "breather" passage, also serves to exhaust fluid which may be received by the chamber 21 if the hammer bar is permitted to withdraw from the bore 20. In the submitted embodiment of my invention the exhaust port 19 hereinbefore referred to, communicates with the passage 22, which, as illustrated by Fig. 2, leads into the rear head structure where it communicates with the passage 30 carrying the exhaust discharged by the valve 23. In this connection it will be understood that sludge, water and other foreign material is liable to collect in the chamber 21 of the front head structure receiving the hammer bar and the rear end of the drill steel. The passage 22 serves in the present embodiment of my invention not only as a breather passage for the chamber 21 and as an exhaust port if the hammer bar withdraws from the bore 20, but also as a drainage passage for the chamber 21. Expulsion of material collected by the passage 22 is aided by the exhaust fluid discharged into said passage from the exhaust port 19 and likewise may be aided by the exhaust fluid discharged by the exhaust passage 30.

Motive fluid for operating the machine is supplied to the valve and therethrough to the conduit 12 by means of a passage 37 formed in the rear cylinder head structure.

The exhaust passage 30 and the passage 22 hereinbefore referred to may unite in the rear cylinder structure as is shown by Fig. 2 whence they pass to the atmosphere.

For controlling the inlet passage 37 and the passages 22 and 30 I employ a suitable valve 38 provided with a manipulating handle 39. This valve as shown is formed with a longitudinal passage 40 for constantly receiving motive fluid from the air line or other motive fluid supply connection, and communicating with the passage 40 is a transverse passage 41 adapted to be placed in communication with the passage 37. The valve is provided with a second transverse passage 42 adapted to establish communication between a port 43 and the terminus of the passages 22, 30. As this type of valve is quite common in the art it is believed that further description of the construction thereof is unnecessary.

The valve 38 just referred to may be manipulated to cut off both the communication between the motive fluid supply and the inlet passage 37 and that between the atmosphere and terminus of the passages 22, 30 and simultaneously therewith to establish communication between the supply passage 41 and the terminus of the passages 22, 30

as will be obvious from Fig. 2 if the valve is considered as turned in a counterclockwise direction. Under these conditions the hammer does not operate and the motive fluid is led by means of the passage 22 to the chamber 21.

For conducting motive fluid to the work, I form the drill steel 4 with the bore 44 leading to the cutting end thereof and communicating at its rear end with the chamber 21. When the chamber 21 is supplied with live air the same will pass into the bore 44 and be discharged in such a manner as to cleanse the work, likewise, under normal operating conditions some of the motive fluid discharged by the exhaust passages 19 and 30 finds its way into the chamber 21 and discharges into the bore 44, while if I permit my hammer bar 8 to withdraw from the bore 20 additional air is supplied the bore 44 from the chamber 8'.

As illustrated suitably supported in the rear head is a tube 45 for conducting water or other suitable cleansing fluid to the bore 25 of the drill steel, the tube for this purpose communicating by means of the passage 48, with the chamber 46 supplied with fluid from a connection 47. This tube passes through and is surrounded by the annular 30 shell valve 23, the chuck rotating motor, conduit 12 of the plug 11 and the piston and hammer bar.

To form a front head structure I have shown the front end of the cylinder member 35 1 as formed with a flange 49 which supports a corresponding flange portion 50 of the chuck casing 51, the cylinder member and the flanges 49 and 50 forming a case for the reduction gearing.

40 In the embodiment of my invention submitted, the chuck 9 is provided with exterior bearings 52, 53 at its forward and rearward ends respectively these bearings respectively engaging the chuck casing and the cylinder. Intermediate these bearings the chuck casing is shown as provided with a gear toothed portion 54 while surrounding this toothed portion is a yoke member 55 having a gear toothed portion 56 in mesh 50 with the gear toothed portion of the chuck. Suitable means may be provided for operating the yoke and for this purpose the opposite ends of the yoke are herein shown as apertured to receive suitable eccentrics 57 which when rotated give the yoke a gyroscopic motion such as to roll its toothed portion about the toothed portion of the chuck and thereby rotate the latter. For each gyration of the yoke, the chuck is advanced 55 a distance corresponding to the difference of the number of teeth on the respective toothed portions and in this way a powerful, compact and efficient speed reducing means is provided.

55 The motor for driving the chuck as il-

lustrated comprises the central gear member 7 and the side gear members 6 meshing therewith, the gear member 7 constituting the rotor and the gear members 6 the rotary abutments of the rotary piston motor. The 70 rotor 7 is mounted on the sleeve member 59 having a flanged portion 60, and coaxing with the sleeve 59 and flange 60 to form a casing for the motor is a member having a flanged portion 61 and a peripheral portion 75 62.

In the flanged portion 60 just referred to, are mounted bearing members 63, while in the flange 50 of the chuck casing are mounted other bearing members 64, these bearing 80 members serving to support shafts 65 carrying at one of their ends the eccentrics 57 and at the other of their ends the gear members 6. These gear members may be removably secured to the shafts and for this purpose are shown the keys 66 integrally formed with the shafts and coaxing with suitable grooves in the gear members.

For holding the cylinder and the flange 90 61 in alignment I have shown sleeve members 76, which also provide additional bearings for the rearward ends of the shafts, additional bearings for the forward ends of the shafts being provided by the reduced diameter portions 77 of the bores 82 formed in the oppositely extending portions 81 of the cylinder as shown in Fig. 1. These extensions 81 with their bores 82 serve to house the shafts.

Motive fluid for operating the chuck rotating motor is supplied by passages 78 leading from the motive fluid supply conduit, said passages being adapted to convey motive fluid to the motor inlet ports 79 formed in the peripheral portion 62 of the 105 motor casing. Exhaust ports for the motor are provided by the passages 80 extending through the walls of the portion 62.

The gear members 6 of the chuck rotating motor as illustrated are of smaller diameter 110 than the central gear member 7. In this connection it will be seen from an inspection of Figs. 3, 4 and 5 that herein the chuck rotating motor, its reduction gearing and the cylinder are generally speaking elliptical in outline. It will further be noticed from an inspection of Figs. 3 and 5 that herein the motor and the gearing are substantially of the same size and from an inspection of Fig. 2 that the short axis of 115 the gearing, the motor and cylinder are substantially of the same dimension. As the corresponding long and short axis of the motor, cylinder and gearing are herein superimposed one upon the other in the assembled machine, a flat sided structure results which adapts the machine to be used in confined situations.

The supporting means for the machine is shown as a handle member having a base 120 67 130

to which is secured the valve cap 69 and the base 68 of the plug 11. The cap 69 and base 68 are recessed to receive the valve 24 and together with the projecting portion 70 of the supporting member form a casing for the valve. The handle member base 67, the cap 69 and plug base 68 are suitably apertured to receive the bolts 71, which are provided with heads 72 having flattened portions 72' (Fig. 4) coating with the interior wall of the sleeve 59 to prevent turning of the bolts.

For holding the front and rear head structures in assembled relation with the cylinder member I have shown yoke members 73. These yoke members are held in place by means of suitable set screws 74 and intermediate their length are supported by suitable lugs 75 formed on the extensions 81 of the cylinder.

In respect to the means for rotating the chuck the rock drill disclosed herein is an improvement over the inventions disclosed in my copending applications Serial No. 350,577, filed January 10, 1920 and Serial No. 354,536, filed January 28, 1920.

It will be understood that I am not limited to the embodiment of the invention disclosed herein and that within the scope of the invention wide deviations may be made therefrom without departing from its spirit.

Claims:

1. In a drilling machine, a cylinder, a rotary chuck, a drilling tool carried by said chuck, a rear cylinder head comprising an annular motor casing, means for supplying said cylinder with motive fluid through the interior of said annular casing, motor means in said motor casing for rotating said chuck, and an operative connection between said motor and said chuck.

2. In a drilling machine, a cylinder, a drilling tool, a rear cylinder head, a motor housed by said rear cylinder head, said motor comprising a plurality of meshing gear members one of which is parallel to the axis of said cylinder and is carried by a shaft extending longitudinally of said cylinder, chuck means adjacent the front end of the cylinder for rotating the tool, and a high ratio speed reducing connection between said means and shaft.

3. In a drilling machine, a cylinder, a gear member located substantially coaxially therewith and rearwardly thereof, a second gear member meshing with the first gear member and being parallel thereto, a shaft driven by said second mentioned gear member, a chuck located adjacent the front end of said cylinder, and high ratio reduction gearing of the gyratory type for operatively connecting said chuck and said shaft.

4. In a drilling machine, a cylinder, front and rear head structures mounted on said cylinder, a fluid operated rotary motor housed

in one of said structures, said motor delivering continuous uni-directional motion and being arranged coaxially of said cylinder, high ratio speed reducing gearing housed in the other of said structures, and driving means connecting the motor and gearing.

5. In a drilling machine, a cylinder, front and rear head structures mounted on said cylinder, spaced oppositely rotating gear members housed in one of said structures, high ratio reduction gearing comprising an annular gear mounted for gyratory movement about the axis of said cylinder housed in the other of said structures, shafts carrying said gear members and being driven thereby, and driving means between said shafts and gearing.

6. A drilling machine having in combination, a cylinder, a piston in said cylinder, a distributing valve for controlling motive fluid for actuating said piston, a chuck, a motor for actuating said chuck, reduction gearing connecting said motor and chuck, a head structure housing said valve and motor, said motor having an annular member operated upon by pressure fluid and located substantially coaxially with said piston, and said distributing valve being surrounded by said annular member.

7. In a drilling machine, a cylinder, a piston in said cylinder, a distributing valve for controlling motive fluid for actuating said piston, a drill rotating motor, said motor surrounding and being located coaxially with said distributing valve.

8. A drilling machine having in combination, a cylinder, a piston in said cylinder, a distributing valve for controlling motive fluid for actuating said piston, a drill rotating motor comprising an annular rotary member for converting the energy of pressure fluid into work and located substantially coaxially with said piston, said annular member surrounding said distributing valve.

9. In a drilling machine, a cylinder, a piston in said cylinder, a distributing valve for controlling motive fluid for actuating said piston, a casing therefor, a drill rotating motor comprising a rotary member for converting the energy of pressure fluid into work, said member being rotatably mounted on said casing and surrounding said distributing valve.

10. In a drilling machine, a drilling tool, a cylinder having a piston chamber, a piston in said cylinder for operating said tool, a chuck, a reversible drive for said chuck comprising a fluid actuated motor and spur reduction gearing, said motor comprising a spur gear member, said member being located rearwardly of said chamber and having continuous rotation, said reduction gearing comprising a gear having a gyratory movement located forwardly of said chamber, and a shaft longitudinally disposed with

relation to said cylinder carrying said spur gear member and operatively connected to said gearing.

11. In a drilling machine, a drilling tool, 5 a cylinder having a piston chamber, a piston therein for operating said tool, a chuck, a reversible drive for said chuck comprising a fluid actuated motor and spur reduction gearing, said motor comprising a spur gear member, said member being located rearwardly of said chamber, said reduction gearing comprising a gear having a gyratory movement, and a shaft longitudinally disposed with relation to said cylinder carrying said spur gear member and operatively connected to said gearing.

12. In a drilling machine, a drilling tool, a cylinder having a piston chamber, a plurality of shafts longitudinally disposed with 20 relation to said cylinder, a fluid actuated motor comprising spur gear wheels located rearwardly of said chamber, high ratio reduction gearing of the gyratory type for rotating said tool located forwardly of said chamber, said spur gear members and gearing being operatively connected to and carried by said shafts.

13. In a drilling machine, a drilling tool, a cylinder having a piston chamber, a plurality of shafts longitudinally disposed with 25 relation to said cylinder, meshing gear members having continuous rotary motion and being located rearwardly of said chamber, high ratio reduction gearing for rotating said tool and being located forwardly of said chamber, and said gear members and gearing being operatively connected to said shafts.

14. In a drilling machine, a cylinder, front 40 and rear head structures therefor, a chuck, a chuck rotating motor delivering continuous uni-directional motion and located in said rear head structure, a high ratio reduction gearing operatively connected to said motor and chuck located in said front head structure, said reduction gearing comprising an annular gear gyrated about the axis of said chuck and cylinder, said motor and gearing each having a long and short axis, 45 and the corresponding axis of each being substantially superimposed whereby is afforded a flat sided arrangement of the enumerated superimposed parts.

15. In a drilling machine, a cylinder, front 55 and rear head structures therefor, a chuck, a chuck rotating motor delivering continuous uni-directional motion and located in said rear head structure, a high ratio reduction gearing operatively connected to said motor and chuck located in said rear head structure, said gearing comprising a gear mounted for gyratory movement about the axis of said cylinder and chuck, said cylinder, motor and gearing each having a long and short transverse axis, and the

corresponding axis of each being substantially superimposed whereby is afforded a flat sided arrangement of the enumerated superimposed parts.

16. In a drilling machine, a cylinder, 70 front and rear head structures therefor, a chuck, a chuck rotating motor delivering continuous uni-directional motion and located in said rear head structure, a high ratio reduction gearing operatively connected to said motor and chuck located in said front head structure, said motor and gearing being reversible, said head structures each having a long and short axis, and the corresponding axis of each being substantially superimposed whereby is afforded a flat sided arrangement of the enumerated 75 superimposed parts.

17. In a drilling machine, a cylinder, front and rear head structures therefor, a chuck, 80 a chuck rotating motor delivering continuous uni-directional motion and located in said rear head structure, a high ratio reduction gearing of the gyratory type operatively connected to said motor and chuck 85 located in said front head structure, said motor and gearing being reversible and each having a long and short axis, and the corresponding axis of each being substantially superimposed and embraced within the projected confines of the other whereby is afforded a flat sided arrangement of the enumerated 90 superimposed parts.

18. In a drilling machine, a cylinder, front and rear head structures therefor, a chuck, 100 a chuck rotating motor delivering continuous uni-directional motion and located in one of said head structures, a high ratio reduction gearing of the gyratory type operatively connected to said motor and 105 chuck located in the other of said structures, said gearing comprising an annular internal gear meshing with an external gear for said chuck, said head structures each having a long and short axis, and the corresponding short axis of each being substantially superimposed and embraced within the projected confines of the other whereby is afforded a flat sided arrangement of the 110 enumerated superimposed parts.

19. In a drilling machine, a cylinder, front and rear head structures therefor, a chuck, a chuck rotating motor, delivering continuous uni-directional motion and located in one of said head structures, a high ratio reduction gearing of the gyratory type operatively connected to said motor and chuck located in the other of said structures, said head structures and cylinder each having a long and short axis, and the corresponding 120 short axis of each being substantially superimposed and embraced within the projected confines of the other whereby is afforded a flat sided arrangement of the enumerated 125 superimposed parts.

20. In a rock drill, a cylinder, a hammer piston in said cylinder, a chuck, a drill steel carried by said chuck and actuated by said piston, front and rear head structures for said cylinder, a reversible motor and reduction gearing for said chuck, said motor comprising three meshing gear members in said rear head structure, said gearing comprising an annular gear surrounding said chuck and through which percussion is imparted to the bit of said drill steel, and eccentric means driven by said motor for giving said gear a gyroscopic motion about said chuck.
21. In a rock drill, a cylinder, a hammer piston in said cylinder, a front head structure having therein a chuck mounted for rotation relatively to said cylinder, a drill steel carried by said chuck and actuated by said piston, an external spur gear for said chuck, an internal spur gear surrounding said external spur gear and meshing therewith a pair of eccentrics in said front head structure at opposite sides of said chuck, said eccentrics carrying said internal gear, shafts carrying said eccentrics and extending rearwardly beside said piston to a rear cylinder head for said cylinder, three meshing gear members in said rear head, two of said gear members being carried by said shafts and the other being in the form of a ring coaxial with said cylinder, a casing surrounding said gear members, means for admitting motive fluid to said casing for operating said gear members, and means for admitting motive fluid for actuating said piston through said gear member in the form of a ring.
22. In a rock drill, a cylinder, a hammer piston in said cylinder, a front head structure having therein a chuck mounted for rotation relatively to said cylinder, a drill steel carried by said chuck and actuated by said piston, an external spur gear for said chuck, an internal spur gear surrounding said external spur gear and meshing therewith, a pair of eccentrics in said front head structure at opposite sides of said chuck, said eccentrics carrying said internal gear, shafts carrying said eccentrics and extending rearwardly beside said piston to a rear cylinder head for said cylinder, three meshing gear members in said rear head, two of said gear members being carried by said shafts and the other being in the form of a ring coaxial with said cylinder, a casing surrounding said gear members, means for admitting motive fluid to said casing for operating said gear members, and a distributing valve for said piston surrounded by said gear member in the form of a ring.
23. A drilling machine having in combination, a cylinder, a piston in said cylinder, a distributing valve for the motive fluid actuating said piston, a casing for said valve, a chuck, a chuck rotating motor comprising a rotary fluid actuated member, reduction gearing connecting said motor and chuck, and said member surrounding said casing.
24. A drilling machine having in combination, a cylinder, a piston in said cylinder, a distributing valve for the motive fluid actuating said piston, a casing for said valve, a chuck, a chuck rotating motor comprising an annular member, reduction gearing connecting said motor and chuck, said member surrounding said casing, and a head structure for said cylinder surrounding said casing.
25. In a drilling machine, a cylinder, said cylinder having a chamber containing a piston, means for admitting and exhausting motive fluid to and from said cylinder including a hollow valve located exteriorly of the cylinder chamber, other means for conducting motive fluid to said cylinder including a passage extending through said valve, and means for conducting fluid to the work including a conduit extending through said valve.
26. In a drilling machine, a cylinder, a piston, means for admitting and exhausting motive fluid to and from said cylinder including a bar providing a conduit extending into said cylinder, means to conduct fluid to the work, said last mentioned means including a conduit extending through said first mentioned means, and a distributing valve controlling the motive fluid for actuating said piston carried by said bar.
27. In a drilling machine, a cylinder, a piston provided with a motive fluid chamber, a bar extending into said cylinder and providing a conduit connecting said chamber with a source of motive fluid supply, means for conducting fluid to the work, said last mentioned means including a conduit extending through said first mentioned conduit means, and a distributing valve controlling the motive fluid for actuating said piston carried by said bar.
28. In a drilling machine, a cylinder, a piston, means for admitting and exhausting motive fluid to and from said cylinder including means providing a conduit extending into said cylinder, means to conduct fluid to the work, said last mentioned means including a conduit extending through said first mentioned means, and a hollow distributing valve the interior of which forms part of said first mentioned conduit surrounding said last mentioned conduit.
29. In a drilling machine, a cylinder, a piston therein provided with a motive fluid chamber, conduit means connecting said chamber with a source of motive fluid supply, means for conducting fluid to the work, said last mentioned means including a tube extending through said first mentioned con-

- quit means, a hollow distributing valve the interior of which forms part of said conduit means, and said valve surrounding said tube.
- 5 30. In a drilling machine, a cylinder, a piston therein provided with a motive fluid chamber, a tubular member connecting a source of motive fluid supply with said chamber, a hollow drill steel, and means for 10 conducting fluid to said steel including a tube passing through said tubular member, a hollow distributing valve the interior of which is in fluid communication with said tubular member, and said valve surrounding 15 said tube.
31. In a drilling machine, a cylinder, a piston, a valve for controlling the motive fluid for actuating said piston, a chuck, a hollow drill steel carried by said chuck, a 20 motor for rotating said chuck having an annular rotary motor member surrounding said valve, and a tube for conducting fluid to said hollow steel and passing through said valve.
- 25 32. In a drilling mechanism, the combination with fluid pressure operated mechanism for imparting a blow to a tool, of means providing a plurality of chambers for receiving said mechanism, a hollow drill steel 30 communicating with one of said chambers, a breather passage for the last mentioned chamber, and an exhaust port for another of said chambers communicating with said breather passage.
33. In a drilling mechanism, the combination with fluid pressure operated mechanism for imparting a blow to a tool, of means providing a plurality of chambers for receiving said mechanism, a hollow drill steel 40 communicating with one of said chambers, a breather port for the last mentioned chamber, one or more exhaust ports for other of said chambers, and conduit means connecting said ports to each other and to the atmosphere.
- 45 34. In a drilling machine, a piston, fluid pressure means for operating said piston including an exhaust port, a tool holder, a hollow drill steel supported by said holder, a 50 drainage passage for said holder, and conduit means connecting said exhaust port to said holder.
- 55 35. In a drilling machine, a tool holder, a hollow drill steel supported by said holder, a drainage passage for said holder, and means to aid the discharge from said passage including conduit means for injecting fluid thereinto.
- 60 36. In a drilling mechanism, the combination with fluid pressure operated mechanism for imparting a blow to a tool, of means providing a plurality of chambers for receiving said mechanism, a breather passage 65 for one of said chambers, an exhaust port for another of said chambers communicating with said breather passage, conduit means connecting said breather passage to the work, and means for connecting said passage to a source of fluid pressure.
37. In a drilling mechanism, the combination with fluid pressure operated mechanism for imparting a blow to a tool, of means providing a plurality of chambers for receiving said mechanism, a breather port for one of said chambers, one or more exhaust 70 ports for other of said chambers, conduit means connecting said ports to each other and to the work, and means for connecting said conduit means to a source of fluid.
38. In a drilling machine, a piston, fluid pressure means for operating said piston including an exhaust port, a tool, a tool holder, a hollow drill steel carried by said tool holder, a drainage passage for said holder, conduit means connecting said exhaust port to said holder, and means for connecting said drainage passage to a source of fluid.
39. In a drilling machine, a chuck, a hollow drill steel carried by said chuck, a passage for connecting the chamber of said chuck with the atmosphere, and means for interrupting such connection and supplying pressure fluid to said passage.
40. In a drilling machine, a chuck, a hollow drill steel carried by said chuck, a passage for connecting said chuck with the atmosphere, and a single valve for interrupting such connection and supplying pressure fluid to said passage.
41. In a drilling machine, a hollow drill 100 steel, a hammer motor for operating said steel, an exhaust passage for said motor in continuous communication with said steel, and means for at will supplying live pressure fluid to said passage.
42. In a drilling machine, a chuck, a hollow drill steel carried thereby, a chuck rotating motor, a hammer motor, an exhaust passage for said hammer motor connected to said hollow steel, an intake passage for supplying both of said motors with operating fluid, and a valve for supplying live fluid to said exhaust passage and for interrupting the supply to said intake passage.
43. In a drilling machine, a chuck, a hollow drill steel carried thereby, a chuck rotating motor, a hammer motor, an exhaust passage for said hammer motor connected to said hollow steel, an intake passage for supplying both of said motors with operating fluid, and a valve for controlling both of said passages and having a position wherein the exhaust passage is supplied with live fluid.
44. In a percussive rock drill, a cylinder, 125 a chambered piston in said cylinder, a hollow drill steel operated by said piston, a tubular member carried at the rear of said cylinder and extending into said piston, a distributing valve carried interiorly of said tubu- 130

lar member, and a cleansing fluid tube extending through said valve and said tubular member.

45. In a drilling machine, a hammer cylinder, a piston hammer, a chuck, a motor for rotating said chuck, said motor carrying a distributing valve for said hammer, a casing for said distributing valve, and said motor and distributing valve forming a rear head for said cylinder.

46. In a drilling machine, a hammer cylinder, a hammer piston, a chuck, a chuck rotating motor, a distributing valve for said hammer, said valve being arranged coaxial-

ly with said hammer, said motor surrounding said valve, and a casing for said valve

and motor forming a rear cylinder head for said cylinder.

47. In a drilling machine, a hammer cylinder, a hammer piston in said cylinder, 20 said hammer piston having a head with an exterior rearward working pressure surface and an exterior forward working pressure surface, a motor carried by said cylinder rearwardly of said piston head for rotating 25 said chuck, said motor having an annular rotor, and said rotor surrounding means for controlling the flow of motive fluid to opposite sides of said piston head.

In testimony whereof, I have signed my 30 name to this specification.

GEORGE H. GILMAN.

Certificate of Correction.

It is hereby certified that in Letters Patent No. 1,605,714, granted November 2, 1926, upon the application of George H. Gilman, of Boston, Massachusetts, for an improvement in "Drilling Machines," errors appear in the printed specification requiring correction as follows: Page 5, line 88, claim 17, after the word "head" strike out the comma; page 7, line 96, claim 40, after the word "connecting" insert the words *the chamber of*; and that the said Letters Patent should be read with these corrections therein that the same may conform to the record of the case in the Patent Office.

Signed and sealed this 4th day of January, A. D. 1927.
[SEAL.]

M. J. MOORE,
Acting Commissioner of Patents.
